UNITED STATES PATENT OFFICE.

JULES RENÉ BLUM, OF PARIS, FRANCE, ASSIGNOR TO THE INTERNATIONAL ASPIRATOR COMPANY LIMITED, OF LONDON, ENGLAND.

DUST-REMOVING PNEUMATIC MACHINE

No. 917,993.

Specification of Letters Patent. Patented April 13, 1909.

Application filed November 29, 1907. Serial No. 404,363.

To all whom it may concern:

Be it known that I, JULES RENÉ BLUM, citizen of France, residing at 9 Rue de l'Isly, Paris, France, have invented new and useful Improvements in Dust-Removing Pneumatic Machines, of which the following is a specification.

This invention relates to improvements in dust removing pneumatic machines and has for its principal object an improved construction of the filtering device whereby the filtering material may be easily cleaned from outside without it being necessary to unmount the casing in which said device is inserted and whereby the dust accumulated after a certain time in said casing may be easily removed therefrom owing to the very simple locking means of the filtering device in its casing.

20 A further object of the invention is to provide for a new arrangement of the suction device capable of being adapted to the filtering device in such a manner that it occupies the smallest space possible.

25 In the accompanying drawings, Figure 1 is a vertical sectional view of the machine, Fig. 2 is a horizontal sectional view taken through line B—B of Fig. 1, and Fig. 3 is a vertical sectional view of the lower part of 30 the machine showing a modified form of construction of the controlling means of the suction device of the machine. Fig. 4 is a detail plan of the cover securing means.

Referring to Fig. 1, it may be seen that 35 the filtering device is inclosed in a sheet metal box *a* having a round opening large enough to allow of free passage to the filtering device. This opening is closed by a cover *b* by means of a bayonet joint. For 40 this purpose the box *a* is provided with a certain number of lugs *c*, of which only one is shown in the drawing, and the rim *b'* of the cover is provided with a number of slots corresponding to the number of lugs.

45 The cover *b* has formed in its center a tubular extension *d* adapted to fit snugly in an opening in a partition *e* of the casing *f* of the machine. Opposite the tubular extension *d* and rigidly secured to the cover *b* is 50 arranged a flange *g* from which extends a receptacle formed of metallic hoops *h*. This receptacle is inclosed in an envelop or shell *i* of loose fibrous material or the like adapted to retain the dust and to let pass there- 55 through only the air. The dust-laden air is

sucked through a tube *a'* connected through the casing *f* with the suction nozzle not shown in the drawings.

The filtering material is adapted to be cleaned by means of a sheet metal brush operated from outside by a crank handle *j*. This brush consists of a rod *k* with a series of thin sheet metal blades *l* secured thereto with close adjacent edges and having their free ends adapted to bear against the filtering material. The rod *k* is bent on one end to form a crank as at *m* and this crank is secured to the same pin *n* as the crank handle *j*. The pin *n* which is mounted on suitable bearings in the top of the box *a*, and the removable lid of the casing *f* is preferably provided with annular grooves *n'* adapted to prevent the dust from passing through the box *a*. The other end of the rod *k* is extended forming an angle arm *o* which is guided during the rotation of the brush in a groove *p* formed in the cover *b* of the box *a*. To remove the lid it is only necessary to remove the handle *j*, after having unscrewed the nut which maintains it in place.

It is obvious from the above description that by rotating the crank handle *j*, the sheet metal blades *l* are caused to rub the filtering material and thus detach the dust retained thereby.

After a certain quantity of dust has accumulated in the box *a* it may be discharged by removing the whole box from the top of the casing *f* and by unlocking then the cover *b* as may be easily understood.

The suction device of the machine comprises three bellows *q* the movable flaps of which are mounted on a single stationary flap *r* parallel with the partition *e* of the casing. The movable flaps are controlled by three depending links *s* connected to a winch driving shaft *t* having three cranks arranged at 120° one from each other. Rotary motion is imparted to shaft *t* either by a belt and a hand wheel as seen in Fig. 1 or by an electric motor and gear wheels as seen in Fig. 3.

The space comprised between the flap *r* and the partition *e* is divided into a large and a small compartment *u* and *v* respectively. The tubular extension *d* and flange *g* of the filtering device lead into the large compartment *u* and the suction valves *w* of the bellows also open into said compartment. On the other hand, the compartment *v* is pro-

vided with inlet valves x and a discharge opening y .

As may be easily understood, the dust-laden air is sucked through the filtering material which retains the dust, and the pure air is sucked by the bellows through the tubular extension d and flange g and the suction valves w , and is expelled through the valves x and the discharge opening y .

10. An adjustable valve z may be provided on the partition e to reduce more or less at will the degree of vacuum in the suction compartment u .

Having now described my invention, what 15 I claim as new and desire to secure by Letters Patent is:

1. In a machine for removing dust by suction, a filtering device comprising a metal box with which the suction nozzle communicates, said box having an opening in its bottom, a removable cover for said opening having an upwardly extending flange and a downwardly projecting tubular extension, said cover having an annular groove formed 25 on its interior around the flange, a suction device communicating with the tubular extension, a receptacle formed of metallic hoops, and a filtering envelop, and extending upwardly from the flange, a brush comprising 30 a rod and a series of thin sheet metal blades having their edges in close contact and adapted to bear against the filtering envelop, a crank arm secured to each end of the rod, one of said arms being guided in the 35 annular groove, and a handle connected to the other arm.

2. In a machine for removing dust by suction, a filtering device comprising a sheet metal box a into which leads the suction

40 nozzle, the bottom wall of the box having an opening therein, a cover b adapted to be locked against the opening of the box by means of a bayonet joint, a downwardly projecting tubular extension on the cover and an upwardly extending flange thereon, a receptacle formed of metallic hoops h and extending upwardly from the flange, a filtering envelop or shell i arranged around the receptacle of metallic hoops, in combination 45 with a horizontal partition e provided with a hole into which is fitted the tubular extension, three bellows q having movable flaps 50 a single stationary flap r parallel with the partition e and on which the flaps are mounted, a vertical partition dividing the 55 space comprised between the flap r and the horizontal partition into a large compartment u and a small compartment v , suction valves w opening into the large compartment, valves x connecting the bellows with 60 the small compartment, said flap r having a discharge opening y connecting the small compartment with the outside air, a winch driving shaft t having three cranks arranged at 120° one from each other, three depending 65 links s connecting the movable flaps of the bellows to the cranks of the driving shaft, and means for imparting rotary motion to shaft t substantially as described and for the purpose set forth.

In testimony whereof I have signed my name to this specification in the presence of two subscribing witnesses.

JULES RENÉ BLUM.
